BRUCE H. TINGLEY, OF CINCINNATI, OHIO, ASSIGNOR TO THE DALTON ADDING MACHINE COMPANY, OF CINCINNATI, OHIO, A CORPORATION OF OHIO.

AUTOMATIC SHUTTLE-CONTROL MECHANISM FOR ADDING MACHINES.

Application filed July 28, 1923. Serial No. 654,453.

The object of this improvement is to provide means for automatically controlling the movement of the shuttle paper carriage at the will of the operator so as to greatly widen the field of use of this feature.

In the customary arrangement of shuttle carriage mechanisms, the carriage usually shuttles from one side to the other after each handle pull, and therefore lists two columns. When items are listed in one of the columns the paper does not space, thus causing items in the two columns to print directly opposite each other. The mechanism is also usually arranged to non-add in one column and to add in the other, thereby greatly simplifying the work of listing car number and amounts, voucher number and amounts, dates and amounts or any similar work where one column should add and the other merely designate.

This shuttling of the carriage usually continues on every stroke of the handle until the operator disables the mechanism by manual movement of a control button. But, with this improved device, the shuttle mechanism is automatically disabled at the will of the operator and four columns of work may be listed with a carriage that only shuttles in two positions, that is, which shuttles first to the right where two columns of work are entered and then shuttles to the left where two more columns are listed, all four columns being entered on a single line. The two columns on the left would ordinarily be non-added and the two on the right would add.

With this device the operator can also list a single column when the carriage is to the right and it will then immediately shuttle to the left and not space the paper, and then another column can be entered and the carriage will not shuttle or not space, but when the next or third item is entered the carriage will shuttle and will space, thus causing three items to be printed in a single line, the first of which would not add and would therefore be a designating number, while the numbers in the second and third columns would add.

Two columns may also be listed while the carriage is to the right, which would not

add, and one column may then be listed after the carriage shuttles to the left, which would add and which would allow the carriage to shuttle to the right again and to space.

This automatic shuttle disabling mechanism may be set by the operator so that the carriage will shuttle and list only two columns in the usual way or both this mechanism and the shuttle mechanism may be normalized and the machine used for straight adding machine work like any ordinary machine.

The accompanying drawings illustrate the device applied to a Dalton adding machine, although, it is obvious that its use is not restricted to this particular make of machine.

Figure 1 is a side sectional elevation of a Dalton adding machine, showing the relative position of the special automatic shuttle control mechanism;

Fig. 2 is a plan view of the automatic shuttle control mechanism;

Fig. 3 is a fragmentary view of the mechanism disabling the shuttle parts;

Fig. 4 is a sample of the work produced by a machine equipped with the device;

Fig. 5 is a projected view of the shuttle normalizing knob; and

Fig. 6 is a projected view of the automatic shuttle control normalizing lever.

No attempt will be made to describe in detail the operation of the Dalton shuttle carriage machine, as the machine is well understood by those skilled in the art and is described in detail in Patent Number 1,582,830, issued Apr. 27, 1926.

The machine as a whole comprises a base 10 and side walls 11 provided with inturned front flanges 12 and rear flanges 13. The main operating shaft 14 occupies the usual position near the base of the machine and is provided with a fixedly mounted segment 15 which rocks with the main shaft under the pull of the operating handle and imparts the power for shuttling the carriage 16 which carries the paper platen 17 and is mounted to ride back and forth along the double trackway 18, which features are of the usual type and do not require special description. The segment 15 has pivoted

thereto a link 18^a, the upper end of which is pivoted to a bell crank lever 19 pivoted at its elbow to a stud 20 secured to the left side wall of the machine.

6 The upper arm of the bell crank lever is provided with a stud 21 which is adapted to engage the recessed end 22 of a drive latch 23, which is mounted at its rear end on a headed stud 24 carried by a slide bar 25 provided with front and rear slots 26 and 27, which slidably engage with headed studs 28 and 29 respectively, which afford guides for the back and forth movements of the slide bar. It is evident that when the 15 drive latch 23 is lowered, it will engage with the stud 21 on the bell crank 19, so that with each forward movement of the operating shaft, a rearward thrust will be imparted to the drive latch and thence to the 20 slide bar.

The slide bar at its rear end has depending therefrom a bifurcated plate 30 which engages a roller 31 mounted upon an arm 32 pivoted at its center upon a journal post 33, which loosely journals a ratchet wheel 34 provided with teeth 35 adapted to be engaged by the end of a dog 36 which is pivoted to the end of the arm 32 and held in engagement with the ratchet teeth by 30 the action of a spring 37 connecting the dog and arm respectively. Each reciprocation of the slide bar will feed the ratchet wheel one tooth.

The ratchet wheel is rigid with a spur wheel 38 which meshes with a pinion 39 on the lower end of a vertical shaft 40 which is journaled through a lower bracket 41 and an upper bracket 42. The vertical shaft at its upper end carries a disk 43 which mounts 40 a pivot stud 44 to which is pivoted a link 45, the outer end of which is pivoted to a shuttle arm 46, the rear end of which is pivoted to a rear flange 47, and the forward end of which engages a notch 48 in a tubular 45 bar 49, which bar forms a transversely extending portion of the carriage structure. With the train of mechanisms above described in engagement, each complete reciprocation of the operating shaft will cause 50 a shuttling of the carriage first to the right and then to the left.

The mechanism now to be described is designed to disable the normal shuttling operation in conformity with the principles 55 of the present invention.

A normalizing knob 50, within convenient reach of the operator, is mounted upon the lower arm 51 of a bell crank lever 52, which is pivoted at its elbow to a stud 53 carried 60 by a plate 54, secured to the front wall of the machine, and the upper arm of the bell crank lever is provided with a rearwardly turned tongue 55 which is positioned to engage a tongue 56 on the forward end of a 65 lever 57 which is fulcrumed on a shaft 58.

The rear end 59 of the lever bears against a pin 60 laterally projecting from the drive latch 23, so that when the normalizing knob 50 is drawn to the right, (see Fig. 5) the forward end of the lever 57 will be depressed 70 which lifts the rear end of said lever and with it the drive latch 23, thereby disengaging the notch in the drive latch from the stud 21, so that the latter may move rearwardly as the main shaft is operated without imparting a rearward thrust to the drive latch and the slide bar to which the drive latch is connected. This, of course, will have the effect of disabling the shuttling mechanism and preventing transverse movement of the paper carriage. 80

The normalizing mechanism above described is for the purpose of completely disabling the shuttling mechanism, but the mechanism now to be described is for the 85 purpose of controlling the shuttling of the carriage in conformity with the movements of the traveling stop carriage, in which the stops are set up by the actuation of the numeral keys, so that a depression of a predetermined number of numeral keys, as for instance seven, will automatically have the effect of breaking the chain of mechanisms which cause the paper carriage to shuttle 90 when the handle is pulled. 95

The stop carriage is not illustrated for the reason that it is of the well-known type, but the stop carriage is associated with an escapement segment 61 which is carried on the shaft 62 and swings in a horizontal plane 100 step by step as the stop carriage is advanced from order to order. The escapement segment has secured thereto a cam segment 63 terminating in a sloping shoulder 64, which cam segment rides against a roller 65 carried by a slide plate 66 which is normally drawn to the rear by the action of a spring 67 which serves to hold the roller 65 in contact with the edge of the cam segment. As the stop carriage (not shown) advances step 105 by step towards the left under the actuation of the numeral keys, the escapement segment and associated cam segment will move in a clockwise direction, and after a predetermined number of movements, the cam 110 shoulder 64, riding past the roller 65, will permit a rearward movement of the slide plate 66, unless such movement is prevented by mechanism presently to be described. 115

The slide plate 66 is slotted to receive the 120 lower end of a bell crank lever 68 which is pivoted at its elbow to an upstanding bracket 69, and the upper arm of the bell crank lever carries a headed stud 70 which engages with a slot 71 in a link 72, the upper 125 end of which is pivoted to a forwardly extending tongue 73 forming a portion of a swinging bracket 74 which is mounted upon the shaft 58. The swinging bracket 74 also is provided with a depending finger 75 which 130

bears against a stud 76 on an arm 77 which depends from the lever 57 which controls the raising and lowering of the drive latch 23. With this arrangement, a downward movement of the link 72, which automatically takes place after the depression of a predetermined number of numeral keys, will cause a lifting of the drive latch and a disengagement of the shuttling mechanism, so that the latter will remain idle during the operation of the main shaft.

In the above circumstances, it is necessary to provide means for disabling the normal operation of the line spacing mechanism. 15 Such disabling means comprise a block arm 78 which forms a constituent part of the swinging bracket and extends rearwardly therefrom into close proximity with the lower end of a carriage space drive arm 79 mounted upon a shaft 80 which controls the operation of the line spacing mechanisms which impart rotation to the paper platen. When the swinging bracket is actuated in the manner stated the block arm 78 will be 20 lifted into the position shown in Fig. 3, where it will block the advance of the drive arm 79, so that the line spacing mechanism will fail to function.

The automatic mechanism actuated by the 25 slide plate 66 to prevent further shuttling may be disabled by the movement of a control lever 81 projecting from the forward portion of the machine through a slot 82 in a plate 83, best shown in Fig. 6. With the 30 control lever in position marked "S", the connections will be automatically disabled after the depression of a given number of keys, but if the lever is drawn downwardly to the position marked "N" and held in the 35 notch 84, the automatic mechanism will be disabled by the action of a draw rod 85 provided with a finger 86 at its rear end, which finger co-acts with a finger 87 on the forward end of the slide plate 66, so that 40 when the control lever 81 is drawn down it will, through the action of an arm 88 impart a forward movement to the draw rod 85 thereby bringing the fingers 86 and 87 into engagement, so that the slide plate 66 will be 45 locked against rearward movement irrespective of the positioning of the cam segment 63, so that shuttling will take place upon every pull of the handle even though the 50 maximum number of number keys have been 55 depressed.

From the foregoing description, it will readily be understood that work such as shown, for example, in Fig. 4, may be produced, in which work the two left hand 60 columns contain designating numbers and the two right hand columns contain numbers to be added. To perform an operation of the character indicated, the normalizing knob 50 is set to the left in Fig. 5 and the 65 automatic shuttle control lever 81 is set at

"S" as in Fig. 6. The paper carriage should first be moved to the right or non-add position bringing the left hand column of the paper to the printing line, whereupon the item 510 is entered and followed by seven 70 ciphers, thus, 0000000. These ciphers may be entered with the cipher key.

The entering of the ciphers has the effect of moving the escapement and cam segments sufficiently to disengage the shuttling mechanism and block the line spacing mechanism, and as the handle is operated, the item 510 will print, since a split is provided for cutting out the seven ciphers to the right. The introduction of the seven ciphers then 80 has the effect of setting the stop carriage into the left adding section, so that the designating item 510 will be printed in the extreme left column, and with the paper carriage shuttled to the right, the adding mechanisms 85 will be thrown out of commission, through the functioning of mechanism, which forms no part of the present invention, so that the items will be merely listed and not added.

The movement of the handle, although it 90 does not shuttle the paper carriage, has the effect of restoring the stop carriage to the right hand position as is the customary practice, so that the operator is now ready to set up the second column of items beginning with 95 number 215 in the example shown. After setting up this item, the paper carriage, still remaining in the right hand position, will prevent adding, but, in this instance, no ciphers are introduced, so that the printing 100 will be effected by the printing mechanism provided for the lower orders, and the item will be entered in a column to the right of the column previously printed.

Since only three numeral keys were 105 depressed in setting up the item in the second column, the top carriage escapement will not have traveled far enough to disable the shuttling mechanism, so that, in this instance, when the handle is pulled, the carriage will 110 be shuttled to the left or into the position in which the adding mechanism is actuated. The operator, in the example shown, then sets up the item 6357 followed by seven 115 ciphers, which, as before, has the effect of setting up the stop carriage into the left adding section and of disabling the shuttling mechanism, so that on the pull of the handle the item in the third column will be 120 printed at the proper column position and added into the accumulating wheels (not shown) in the usual manner. The stop carriage having been restored to its normal right hand position, the operator is now ready to set up the last item in the extreme 125 right hand column and since no ciphers are added to this item, the carriage will shuttle in the opposite direction.

With the paper carriage in the right hand position for setting up the two non-add 130

columns, the line spacing mechanism will be blocked as the carriage is shuttled by the lifting of the block arm 78 into position to engage the roller on the end of the line spacing arm 79, but when the paper carriage has been shuttled over into the left hand position, the block arm and line spacing arm will occupy positions out of register with one another, so that the lifting of the block arm will be ineffective to prevent a full movement of the line spacing arm. This being the relation of the parts, it follows that when 6357 is set up followed by seven ciphers and the handle has been pulled, the shuttling mechanism is disabled and the block arm lifted into position to prevent line spacing, but after the setting up of the fourth item 51425 which is not followed by ciphers, the operation of the handle will allow both 20 shuttling and line spacing, so that the paper platen will again move to the right position with the paper properly spaced to receive the next horizontal row of figures.

In the example shown, a thirteen column machine is used, two left hand columns being entered with the non-add parts effective to prevent adding while the two right hand columns are listed and accumulated at the same time, there being a split in the adding section 30 to permit such double accumulation.

By entering items into the stop carriage and by throwing these items into a position where the automatic control parts will or will not be effective, it is possible at the will of the operator to either list two non-add columns and one add column or to list one non-add column and two add columns, or by setting the automatic control lever 81 at the point "N" it is possible to list a single non-add column and a single add column, both of which have a capacity of thirteen digits. Also a moving of the control knob 50 to the right-hand position will have the effect of lifting the drive latch and disabling the shuttling mechanism, and this in conjunction with a movement of the control lever to the notch "N" will prevent a blocking of the line spacing mechanism, so that with the control members thus adjusted, all of the 50 special features of the present invention will be thrown out of commission and the machine may be used as an ordinary adding machine.

The invention is one which suitably combines with an adding machine of well known standard type without in any way impairing the adding functions or capacities of the machine, and without necessitating any substantial change or modification of standard equipment and without increasing the bulk 60 of the machine.

I claim:

1. In mechanism of the class described, in combination with the setting up mechanism 65 of an adding machine a laterally movable

paper carriage, shuttling mechanism for the paper carriage, an operating shaft normally effective to actuate the shuttling mechanism, and a member associated with the setting up mechanisms and adapted to disable the shuttling mechanism after a predetermined number of movements of the setting up mechanisms, substantially as described.

2. In mechanism of the class described, in combination with the setting up mechanism 75 of an adding machine, a laterally movable paper carriage, shuttling mechanism for the paper carriage, an operating shaft normally effective to actuate the shuttling mechanism, a member associated with the setting up mechanisms and adapted to disable the shuttling mechanism after a predetermined 80 number of movements of the setting up mechanisms, and a member adapted to prevent the control of shuttling by movements 85 of the last-named mechanism, substantially as described.

3. In mechanism of the class described, the combination of a transversely movable carriage, shuttling mechanism for the carriage, a main shaft and connections for normally actuating the shuttling mechanism by movement of the main shaft, a stop carriage escapement member, and members associated therewith for preventing shuttling 90 after a predetermined degree of movement 95 of said escapement member, substantially as described.

4. In mechanism of the class described, the combination of a transversely movable carriage, shuttling mechanism for the carriage, a main shaft and connections for normally actuating the shuttling mechanism by movement of the main shaft, a stop carriage escapement member, members associated therewith for preventing shuttling after a predetermined degree of movement of said escapement member, and a control member adapted to prevent a disabling of the shuttling mechanism by movements of the 105 escapement member, substantially as described.

5. In mechanism of the class described, the combination of a transversely movable paper carriage, a main operating shaft, shuttling mechanism for the carriage including a swinging arm and connections between said arm and the main operating shaft, a stop carriage escapement member, and means adapted to be actuated after a predetermined movement of the escapement member for breaking the train of connections between the operating shaft and the shuttling arm, substantially as described.

6. In mechanism of the class described, 125 the combination of a transversely movable paper carriage, a main operating shaft, shuttling mechanism for the carriage including a swinging arm and connections between said arm and the main operating 130

- shaft, a stop carriage escapement member, means adapted to be actuated after a predetermined movement of the escapement member for breaking the train of connections between the operating shaft and the shuttling arm, and means for preventing the effective movement of said last named means by movements of the escapement member, substantially as described.
10. In mechanism of the class described, the combination of a paper carriage, a main operating shaft, a shuttling arm engaging the paper carriage, dog and ratchet members and connections for swinging the shuttling arm to effect shuttling, connections between said dog and ratchet mechanism and the main shaft for normally actuating the former by movement of the latter, and means actuated by setting up movements for breaking said shuttling connections after a predetermined number of setting up movements, substantially as described.
8. In mechanism of the class described, the combination of a paper carriage, a main operating shaft, a shuttling arm engaging the paper carriage, dog and ratchet members and connections for swinging the shuttling arm to effect shuttling, connections between said dog and ratchet mechanism and the main shaft for normally actuating the former by movement of the latter, means actuated by setting up movements for breaking said shuttling connections after a predetermined number of setting up movements, and control means adapted to prevent the effective operation of said last named means, substantially as described.
9. In mechanism of the class described, the combination of a transversely movable paper carriage, a main operating shaft, connections between the main operating shaft and the paper carriage for normally shuttling the carriage with each movement of the operating shaft, a rotatably mounted stop carriage escapement member, a cam carried by the said member, a slide plate in engagement with said cam, and adapted to be actuated after the escapement has traveled a predetermined distance, and connections operable by the movement of said slide plate for breaking the train of shuttling connections by movement of said slide plate, substantially as described.
10. In mechanism of the class described, the combination of a transversely movable paper carriage, a main operating shaft, connections between the main operating shaft and the paper carriage for normally shuttling the carriage with each movement of the operating shaft, a rotatably mounted stop carriage escapement member, a cam carried by the said member, a slide plate in engagement with said cam, and adapted to be actuated after the escapement has traveled a predetermined distance, connec-
- tions operable by the movement of said slide plate for breaking the train of shuttling connections by movement of said slide plate, and a line spacing block member adapted to move to blocking position by movement of said slide plate, substantially as described.
11. In mechanism of the class described, the combination of a transversely movable paper carriage, a main operating shaft, shuttling mechanism for said paper carriage, connections between said shuttling mechanism and said shaft for normally effecting a shuttling operation with each movement of the shaft, control means for breaking said shuttling connections, a stop carriage escapement member carrying a cam, mechanism associated with said cam and adapted to be moved after a predetermined number of movements of said escapement member, and connections between said mechanism and the shuttling connections for disabling the latter by movement of said cam controlled mechanism, substantially as described.
12. In mechanism of the class described, the combination of a transversely movable paper carriage, a main operating shaft, shuttling mechanism for said paper carriage, connections between said shuttling mechanism and said shaft for normally effecting a shuttling operation with each movement of the shaft, control means for breaking said shuttling connections, a stop carriage escapement member carrying a cam, mechanism associated with said cam and adapted to be moved after a predetermined number of movements of said escapement member, connections between said mechanism and the shuttling connections for disabling the latter by movement of said cam controlled mechanism, and a control member for preventing movement of said cam controlled mechanism at all stages of movement of said cam, substantially as described.
13. In mechanism of the class described, the combination of a transversely movable paper carriage, a shuttling arm for imparting back and forth movements to said paper carriage, a main operating shaft, connections between said main operating shaft and said shuttling arm for imparting swinging movements to the latter, said connections including a drive latch, a stop carriage escapement member, and means actuated by predetermined movement of said escapement member for effecting disengagement of said drive latch to break the shuttling connections, substantially as described.
14. In mechanism of the class described, the combination of a transversely movable paper carriage, a shuttling arm for imparting back and forth movements to said paper carriage, a main operating shaft, connections between said main operating shaft and

6
said shuttling arm for imparting swinging movements to the latter, said connections including a drive latch, a stop carriage escapement member, and means actuated by predetermined movement of said escapement member for effecting disengagement of said drive latch to break the shuttling con-

nnections, line spacing mechanism, and means for blocking the effective operation of said line spacing mechanism operable by mechanism which effects a disengaging of the drive latch, substantially as described. 10

BRUCE H. TINGLEY.
